UNITED STATES PATENT OFFICE

HOWARD A. SPAHR, OF MILWAUKEE, WISCONSIN

ELECTRIC SWITCH

Application filed October 10, 1927. Serial No. 225,221.

This invention relates to electric switches, and is particularly directed to an electric switch of the push button type, push pull type, or pendant switch type, or others of this type, or general order.

Objects of this invention are to provide a novel form of electric switch which has a quick make and break, which is formed of a very small number of parts, which may be made in any size or capacity, which is extremely compact, and in which the parts are very readily assembled.

Further objects of this invention are to provide a switch which is so constructed that the rocker bar may be positively dislodged by the push button or manually operable member, for instance, in the event that the rocker bar sticks and is not dislodged by the spring action, and to provide a novel form of switch in which the rocker bar has a quick motion imparted thereto for either direction of travel of the reciprocating member.

Further objects are to provide an electric switch of the above type in which no mounting frame is required, but in which the parts rest upon the case and in which the stresses are borne by the rocker arm and reciprocating member and are not transmitted to the case.

Further objects are to provide a switch having a plunger and a rocker bar and a spring in which the spring mounting is such that no additional pins, thimbles, or other spring holding means are required, but instead the spring is so formed that it cooperates directly with the reciprocating member to provide a pivotal mounting for the spring.

Further objects are to provide a switch in which a two part casing may be employed to enclose the switch parts themselves in a novel manner permitting the stresses, as stated, to be borne by the rocker arm and plunger themselves instead of by the case, and without the use of any mounting frame, as stated above, and to provide means for temporarily holding in the screws and the switch parts in the event that one-half of the case is removed to connect up the parts of the switch.

Embodiments of the invention are shown in the accompanying drawings in which:

Figure 1 is a longitudinal sectional view on the line 1—1 of Figure 2;

Figure 2 is a transverse sectional view on the line 2—2 of Figure 1;

Figure 3 is a transverse sectional view on the line 3—3 of Figures 1 and 4;

Figure 4 is a plan view of a part of the casing with the rocker bar and plunger removed;

Figure 5 is a side elevation of a modified form of switch with parts in section;

Figure 6 is a longitudinal sectional view of a further form of switch.

Referring to the drawings, particularly Figures 1 to 4, it will be seen that the switch comprises an upper and a lower casing 1 and 2, respectively, which are held together by means of screws 3. These screws have a reduced shank portion 4 which is smaller than the threaded part 5. Further, it will be seen that the upper casing 1 is bored out, as indicated at 6, and has a threaded portion 7 whose internal diameter is slightly less than the bored out portion 6. This permits the insertion of the screw into the member 1 by screwing it through the threaded portion 7. Thereafter, the screw is held against complete dislodgment from the member 1, although the member may be turned upside down. The reason for this is that the enlarged threaded portion 5 merely contacts with the threaded portion 7 of the casing 1 and prevents the screws from dropping out.

This feature, although apparently only a detail, is nevertheless extremely serviceable in connecting up the switch for it is not necessary to carefully remove the screws to prevent their loss as the screws are automatically held to the upper casing.

Each of the casing members is provided with a cut out portion 8 which together form a main compartment within which the rocker arm 9 is positioned. This rocker arm is provided with a pair of trunnions 10 which may be formed by slipping rings over the projecting ears 11 of the rocker bar, as shown in Figure 3, although obviously other constructions could be used. These trunnions

are received within slots or cutouts 12 formed in the lower casing member 2 and, if desired, a small piece of fibre or fibre paper 13 may be slipped into place above the trunnions to prevent dislodgment of the rocker bar even if the switch is opened and the bottom casing inverted. This construction is shown most clearly in Figures 1 and 2.

It is to be noted further that the upper casing member 1 is provided with a pair of downwardly extending lugs 14 which are positioned within the cutouts 12.

The lower casing member 2, as shown in Figure 4, is provided with two pair of stops 15 which are positioned on opposite sides of the central cutout 8. These stops arrest the motion or limit the extreme motion of the rocking bar 9. Further, as shown in Figure 4, a pair of stationary contact fingers 16 may be provided which, if desired, are made of relatively springy brass or bronze, or other suitable material. Between these spring fingers the upper end of the rocking bar 9 is adapted to be positioned when the switch is closed. It is to be noted also that the stops 15 are positioned inside of the contact 16 and consequently in connecting up the switch, no displacement of the contacts can occur even though the operator's screw driver should strike one of the contacts. This is secured as stated because of the positioning of the stops 15 which act as limiting stops for the stationary contacts also. In addition to this, the stops 15 on the side of the casing from the contacts provide guides for the through wire and thus prevent the wire from becoming entangled with the mechanism.

The lower casing member 2 is provided with a pair of transversely positioned and aligned cutouts 17, similar cutout portions 18 being provided in the upper casing member. These cutout portions receive the insulating handles 19 of the oscillatory or reciprocatory member which operates the rocking bar. The handles are connected by means of a metal body portion 20 and together with this metal body portion form the oscillatory part of the switch. This metal body portion has downwardly projecting lugs 21 which are received within slots 22 formed in the lower casing member, as shown most clearly in Figures 2 and 4.

It is to be noted particularly that the central portion of the rocker bar 9 is cut out and at its upper portion it is provided with a downwardly extending lug 23 which receives the upper end of the compression spring 24. The lower end of the compression spring has its last convolution stopped half-way and has the last strand 25 bent diametrically across the spring, as shown in Figure 2. This provides a centrally located bearing support for the spring which is formed integrally with the spring itself. The oscillatory plunger or member 20 is provided with an upstanding

slotted and externally rounded lip or projection 26 which fits within the body of the spring and whose slot receives the bar 25 of the spring. This construction is shown particularly in Figure 2.

It is to be noted that the lower portion of the rocking bar is provided with a downwardly extending part 9' (see Figure 1) which is equipped with a slot 27 within which the reciprocatory member 20 is slidably received. This reciprocatory member therefore is held against lateral rocking motion with respect to the rocking bar and also holds the rocking bar itself against lateral motion. In addition to this, it may be found desirable to form the handles 19 (see Figure 2) rectangular, and to correspondingly shape the notches or cutouts 17 and 18.

The operation of the switch is as follows:

Assume that the switch is open, as shown in Figure 2, and that the operator presses the button or handle 19 inwardly. This causes the bottom pivot point of the spring to travel to the right in Figure 2, and in addition to this, one of the projecting tongues 21 engages the downwardly extending portion 9' of the rocking bar below the line of the trunnions. This starts the rocking bar and the switch completes the rocking motion in the left hand direction or counter clockwise direction, as viewed in Figure 2. Thus, the switch has a quick make. A reverse motion of the reciprocatory member will cause the other downwardly projecting member 21 to engage the lower end or portion 9' of the rocking bar, and a similar action will take place, the rocking bar then travelling in a clockwise direction back into the position shown in Figure 2. This gives a quick break.

It is also contemplated by this invention to provide a switch in which the spring causes and completes the quick or rocking motion of the rocker bar, and in which the downwardly projecting lugs 21 of the reciprocatory member merely come into engagement with the downwardly projecting portion of the rocker bar when the rocker bar tends to stick.

It is to be noted that the downwardly extending member 9' also acts as a stop for the reciprocatory member as it strikes against one or the other of the lugs 21 at the limit of motion of the switch.

It may be desirable to assemble the parts one from the bottom of the portion of the casing and the other from the top. For instance, as shown in Figure 5, the lower member 28 of the casing is similarly formed to the member 2 of the casing, previously described, except that the trunnion receiving notches or slots 29 open through its bottom edge and also a slot is provided in the bottom edge communicating with these slots 29. The rocking bar 30 is substantially similar to the rocking bar, previously described, except that it has a slot 31 through its upper side which ex-

tends downwardly between the projecting spring receiving lugs 32. This permits the positioning of the reciprocatory member 33. The slot in the bottom portion of the casing 28 is closed in any suitable manner as by means of the insulating block or strip 34.

It is obvious that the switch may be made in other forms. For instance, a push pull switch is illustrated in Figure 6. In this, the same construction of reciprocatory member is followed as in Figure 1, for instance, such member being indicated by the reference character 35. Also, a similar type of rocking bar 36 may be provided for engaging the stationary contacts 37. The spring 38 is mounted in the same way, as previously described. However, the casing members 39 are formed to provide an opening only at one end which receives the fitting 40. This fitting is threaded, as indicated at 41, and is adapted to be passed through a panel and secured by suitable nuts in a well-known manner. The reciprocation member 35 has an extension 42 guided in one end of the casing and at its other end is connected by means of an insulating strip 43 with the operating handle or stem 44. The stem and insulating strip 43 are guided in the fitting 40 and consequently correctly support the outer end of the reciprocatory member 35.

This form of switch can be used as a push pull switch, if desired. In addition to this, it is clear that other forms of switches may be employed which embody the invention disclosed in this case. For instance, the reciprocatory member could be urged in one direction by a spring so that it could be used as an instantaneous switch by merely pressing downwardly or inwardly upon the projecting handle. Obviously, the casing could be changed so that the switch could be a pendant switch without departing from the spirit of this invention.

It is apparent that all of the forces due to the action of the spring may be borne internally, that is to say, may be borne by the reciprocatory member and the rocking bar and the forces of the spring are not then transmitted to the supporting casing. In addition to this, it is also clear that no mounting frame need be used with this switch, thus very markedly simplifying its construction.

It is to be noted also that a novel form of switch has been provided in which no forming operations whatsoever are needed for the mechanism itself, that is to say, for the movable parts. Instead, these movable parts are merely blanked out of sheet material. Obviously, eliminating the forming operations materially reduces the cost of the switch.

It has been found that the frictional loss and consequently the effort required to operate the switch is reduced to a minimum, although a stiff spring may be used. This, therefore, greatly increases the ease of opera-

tion of the switch. Further, it is apparent from the description and the drawings that the switch has a very small number of easily produced parts and that these parts may be assembled with the utmost ease.

70

Although the invention has been described in considerable detail, such description is intended as illustrative rather than limiting as the invention may be variously embodied and as the scope of such invention is to be 75 determined as claimed.

I claim:

1. An electric switch comprising a two-part casing, one of said parts having a threaded aperture, screws carried by the other of 80 said parts and extending into said threaded aperture, said second mentioned part of the casing having a threaded portion through which the threaded portion of the screw may be passed, said screw having a shank of reduced diameter from the external diameter of the threaded part, whereby the screw is prevented from inadvertently dropping from the second mentioned portion thereof, and switch mechanism carried within said casing. 90

2. An electric switch comprising a pivoted rocking bar, stationary contacts adapted to be engaged by said rocking bar, a reciprocatory member for actuating said rocking bar, 95 said rocking bar having a downwardly extending portion, lugs extending downwardly from said reciprocatory member and adapted to engage said downwardly extending portion of said rocking bar during the completion of the stroke of the reciprocatory member in the event that said rocking bar sticks, said downwardly extending portion of said rocking bar also constituting a stop for said lugs to limit the stroke of said reciprocatory member, and a compression spring between 100 said rocking bar and said reciprocatory member. 105

3. An electric switch comprising a base, a pivoted rocking bar carried by said base, stationary contacts adapted to be engaged by said rocking bar, a reciprocatory member for actuating said rocking bar, a compression spring interposed between said reciprocatory member and said rocking bar, said spring holding said rocking bar and said reciprocatory member to said base, said rocking bar having an opening and said reciprocatory member having a portion passing through said opening, and means carried by said reciprocatory member and adapted to engage 110 said rocking bar during the completion of the stroke of said reciprocatory member in the event that said rocking bar sticks. 115

4. An electric switch comprising a casing having a stationary contact, a rocking bar 120 provided with an opening therethrough and provided with trunnions carried by said casing, a reciprocatory member extending through said opening in said rocking bar, a spring interposed between said rocking bar 125

130

and said reciprocatory member, said reciprocatory member having downwardly extending lugs and said rocking bar having a downwardly extending portion adapted to be engaged by said lugs during the completion of the stroke of the reciprocatory member in the event of sticking of the rocking member, said rocking bar having a slot communicating with said opening, whereby said reciprocatory member may be passed through said slot during assembly.

In testimony that I claim the foregoing I have hereunto set my hand at Milwaukee, in the county of Milwaukee and State of Wisconsin.

HOWARD A. SPAHR.
